C. D. HIGGINSON

CHILD'S VEHICLE

Filed Sept. 7, 1926

INVENTOR.
Connan Doyle Higginson.
BY
Cuthbert T. Larrabee
his ATTORNEY

UNITED STATES PATENT OFFICE.

CONNAN DOYLE HIGGINSON, OF LOS ANGELES, CALIFORNIA, ASSIGNOR, BY DIRECT AND MESNE ASSIGNMENTS, OF ONE-HALF TO GEORGE A. PROCTOR, OF LOS ANGELES, CALIFORNIA.

CHILD'S VEHICLE.

Application filed September 7, 1926. Serial No. 133,866.

This invention relates to a child's vehicle adapted when a child is seated thereon, to be straddled and propelled by the action of the child's feet pushing against the surface over which the vehicle travels.

An object of this invention is to provide a new, novel and useful device which is cheap to construct, sturdy, and neat in appearance.

Another object is to provide a novel device of the above character whereby a child in moving the device over a surface by means of the feet will be able to obtain greater exercise of the legs.

Another object is to provide a novel device of this character which is devoid of the usual steering wheel but which may be easily and quickly moved in any direction by a pressure exerted by the feet of the child riding the same.

Other objects, advantages and features of invention may appear from the accompanying drawing, the subjoined detail description and the appended claims.

The accompanying drawing illustrates the invention in a form I at present deem preferable.

Figure 1 is a perspective elevation of child's vehicle constructed in accordance with this invention.

Fig. 2 is a rear elevation of the same.

Fig. 3 is a bottom view with the skirt portion removed.

Fig. 4 is a side elevation with one-half of the skirt portion removed to show the interior construction.

Fig. 5 is a top plan view of the same.

My invention comprises a wheel supported base or supporting frame 1 formed of a relatively long and narrow or elongate member 2 that has a bolster or cross member 3 fixed to its rear end and an upright or post 4 fixed to its forward end. A brace in the form of a block 5 that is secured to member 2 and post 4 by suitable means, such as screws 6, serves to maintain the upright 4 in position. Swivel casters 7 that are preferably rubber tired, are secured to the frame 1 and provide means whereby the vehicle may be easily moved in any direction over the surface on which it is supported.

A seat member 8 comprising a wide seat section 9 and a comparatively narrow elongate portion 10 extending forwardly from

said seat section 9 is pivotally connected or hinged at its forward end as at 11 to the post 4 and is resiliently supported at its rear end by means of a plurality of coil springs 12 that are fastened in place by any suitable means such as staples 13.

The elongate portion 10 is adapted to be straddled by the feet of a child seated on seat 9 and coil springs may be of any suitable number or tension to provide the requisite strength for best operation of the device. Means 14 in the form of a chain is connected to the member 2 and member 8 to limit the rebound action of the seat member.

A head member 15, which may represent a horse's or other animal's head, extends upwardly from the forward end of member 8 and is preferably secured to member 8 by nails or screws *a*, so as to be movable therewith. The combined head and seat structure is pivoted at one end to the upper end of the post 4 by the hinge 11. Hand grip bars 16 are conveniently located on head member 15 and provide means onto which a child may hold when riding on the vehicle.

A skirt or apron 17 of any suitable material, such as awning, is secured around the edge of seat member 8 by means of upholsterers' tacks 18 and such skirt depends therefrom to a point preferably below the base 1 and serves to cover the base and spring structure between the base and seat, and also to provide a neat and pleasing appearance to the vehicle.

A rope or other suitable flexible member 19 is fastened underneath the seat member 8 and protrudes through an orifice 20 in skirt 17 and simulates the appearance of a horse's tail.

A saddle piece 21 is secured to member 10 by tacks 22 and by some of the tacks 18 and adds to the appearance of the device.

Advantages gained by my construction are that a child is afforded a maximum of pleasure in using the same, and will be able to obtain a maximum exercise of the legs due to raising the body off from the seat in order to obtain the up and down movement afforded by the spring support for the seat and which enables a child to ride a vehicle of this character that closely resembles a horse in appearance and action. Furthermore, the vehicle may be moved in any de-

sired direction by merely pushing the vehicle in the desired direction and I thus dispense with the necessity of a swivelly mounted steering post.

5. It will be apparent to those skilled in the art that the device may be made with various heights of the post 4 and lengths of coil springs 12 to vary the height of the seat; or blocks, not shown, may be secured to the 10 underside of the frame and the casters mounted in said blocks to accomplish that result.

I claim:

1. A child's vehicle including a base; 15 swivel casters supporting said base; a post fixed to said base near one end thereof; a seat member; hinge means connecting one end of said seat member to said post; spring means extending between said base and the 20 other end of said seat member adapted to provide a resilient support for the free end of said seat member; a head member extending upwardly from the hinged end of said seat member; hand grip bars extending from 25 said head member; and a skirt secured to said seat member and depending therefrom to cover said spring means.

2. A child's vehicle including a base; swivel casters supporting said base; a post 30 fixed to said base near one end thereof; a seat member; hinge means connecting one end of said seat member to said post; spring means extending between said base and the other end of said seat member adapted to 35 provide a resilient support for the free end of said seat member; means connecting said base and said seat member to limit rebound action of said seat member; a head member extending upwardly from the hinged end of 40 said seat member; hand grip bars extending from said head member; and a skirt secured to said seat member and depending therefrom to cover said spring means.

3. A child's vehicle comprising a base 45 formed of a relatively long and narrow member and having a cross member at its rear end; swivel casters connected to said long and narrow member and to said cross member; a post fixed to the forward end of 50 said long and narrow member; a seat member having a wide seat portion and a comparatively narrow elongate portion adapted to be straddled by a child seated on the vehicle; hinge means connecting said seat member to said post; a head member fixed to said seat member and provided with hand grip bars; spring means extending between 55 said wide seat section and said base adapted to resiliently support said seat member at its free end; and a skirt surrounding said seat member and extending from said seat

member to a point below said base member.

4. A child's vehicle comprising a wheel supported base; a post extending from the forward end of said base; a brace secured to 65 said base and said post; a seat member hingedly connected at one end to said post and resiliently supported from said base at its free end; a head member fixed to said seat member and provided with hand grip bars; 70 a skirt encircling said seat member and extending therefrom so as to conceal said base; and a flexible member secured to the underside of said seat member, said flexible member protruding through said skirt and adapted to simulate the appearance of a horse's tail. 75

5. A child's vehicle including a wheel supported base, a post fixed to the base near one end thereof, a combined head and seat structure pivotally connected to said post, means for resiliently supporting the combined head and seat structure against pivotal movement in one direction, and means directly connecting said structure and base for limiting the 85 upward pivotal movement of the seat structure in the opposite direction.

6. A child's vehicle including a wheel supported base, a post fixed to the base near one end thereof, a combined head and seat structure pivotally connected to said post, a coil spring disposed between the base and the 90 combined head and seat structure for resiliently supporting said structure, and a flexible inelastic connection between the base 95 and the structure for limiting the upward pivotal movement of the structure.

7. A child's vehicle including a wheel supported base, a post fixed to the base near one end thereof, a combined head and seat structure pivotally connected to the post, the seat of said structure being positioned above the base and normally disposed in substantially horizontal parallelism therewith, and means 100 for resiliently supporting said structure 105 against pivotal movement.

8. A child's vehicle including a wheel supported base, a combined head and seat structure pivotally connected at one end thereof to one end of the base, means for resiliently 110 supporting said structure against pivotal movement, a skirt encircling the seat and depending therefrom to conceal the base and the resilient structure supporting means, and a flexible tail secured to the underside of the 115 seat and projecting outwardly through said skirt.

In testimony whereof, I have hereunto set my hand at Los Angeles, California, this 30th day of August, 1926.

CONNAN DOYLE HIGGINSON.
